US00D820220S

(12) **United States Design Patent** (10) Patent No.: **US D820,220 S**
(45) Date of Patent: ** Jun. 12, 2018

(54) **OPERATION BOARD FOR NUMERICAL CONTROLLER**

(71) Applicant: **Mitsubishi Electric Corporation**,
Tokyo (JP)

(72) Inventors: **Shinichi Kato**, Tokyo (JP); **Yuki Mizushi**, Tokyo (JP); **Shoichiro Hayashi**, Tokyo (JP); **Hirohisa Naguchi**, Tokyo (JP)

(73) Assignee: **Mitsubishi Electric Corporation**,
Tokyo (JP)

(**) Term: **15 Years**

(21) Appl. No.: **29/603,504**

(22) Filed: **May 10, 2017**

(30) **Foreign Application Priority Data**

Nov. 15, 2016 (JP) 2016-024811
(51) LOC (11) Cl. 13-03

(57) **CLAIM**

The ornamental design for the operation board for numerical controller, as shown and described.

DESCRIPTION

FIG. 1 is a front, top and right side perspective view of an operation board for numerical controller, showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The parts shown in the broken lines are for the purpose of illustrating portions of the article and do not form part of the claimed designs. Dotted and dashed lines represent boundaries of the claimed design and form no part thereof.

1 Claim, 7 Drawing Sheets

FIG. 1***FIG. 2******FIG. 3******FIG. 4****FIG. 5****FIG. 6***

FIG. 7
